UNITED STATES PATENT OFFICE.

BENJAMIN WOLHAUPTER, OF NEW YORK, N. Y.

COMPOSITE RAIL-TIE.

937,132.

Specification of Letters Patent. Patented Oct. 19, 1909.

Application filed December 23, 1907. Serial No. 407,774.

To all whom it may concern:

Be it known that I, BENJAMIN WOLHAUPTER, a citizen of the United States, residing at New York city, in the county of New York and State of New York, have invented certain new and useful Improvements in Composite Rail-Ties, of which the following is a specification.

This invention relates to the subject of track structures for railways, and has special reference to that type of cross ties which are commonly termed cement or composition ties and employed as a substitute for the ordinary wooden ties generally used.

To this end the invention contemplates a simple and thoroughly practical construction of tie which may be characterized as a composite tie, inasmuch as the same embodies in its organization the general characteristics and advantages of a cement or concrete tie as well as a metallic tie, while also preserving and utilizing the advantages of a wooden tie by providing wooden cushions for the bearing support of the rails.

A general object of the invention is to provide a composite tie possessing in the metal parts ample strength and rigidity to carry the loads required, said metal parts being protected and held in position by concrete.

Furthermore, another object of the invention is to provide a composite tie carrying cushions for the rails of substantially the depth of the tie.

A further object of the invention is to provide for an effective and uniform distribution of the load throughout the tie in connection with the provision of deep cushions for the rails. Also, the invention contemplates a construction wherein any approved or preferred types of rail fastenings may be employed such as can be, and are, employed to fasten rails to the ordinary wooden ties.

A still further object of the invention is to provide a construction of tie wherein the track circuits for signaling purposes are not interfered with in the least, inasmuch as the tie provides for a complete insulation of one rail from the other.

With these and many other objects in view, which will readily appear to those familiar with the art, the invention consists in the novel construction, combination and ar-

angement of parts hereinafter more fully described, illustrated, and claimed.

The essential features of the invention, involved in carrying out the objects above indicated, are necessarily susceptible to a wide range of structural modification without departing from the scope of the invention, but a preferred embodiment thereof is shown in the accompanying drawings, in which:

Figure 1 is a longitudinal sectional view of a complete tie constructed in accordance with this invention, and showing the bearing cushions for the rails in elevation. Fig. 2 is an enlarged sectional view of one end portion of the tie, showing in elevation the bearing cushion for one rail. Fig. 3 is a transverse sectional view on the line 3—3 of Fig. 2. Fig. 4 is a detail in perspective of a portion of one of the reinforcing frame bars. Fig. 5 is a detail perspective view of one form of transverse bracing tie that may be utilized to connect or tie oppositely arranged frame bars.

Like references designate corresponding parts in the several figures of the drawings.

The improved tie contemplated by the present invention primarily consists of a concrete body portion 1, and a plurality of interior metallic bars 2 entirely embedded in, and enveloped by, concrete material, and extending longitudinally thereof, substantially the entire length of the same so as to constitute the metal frame or frame work for the tie body, while at the same time acting in the capacity of reinforcing units to stiffen and strengthen the tie throughout, said metallic bars 2 being, therefore, properly characterized as reinforcing frame bars.

The term "concrete" is used in its general and broad application to comprehend any of the cements or cement composition, such as ordinarily used in structural work of different kinds, so it will be understood that the present invention is not limited to any particular kind of concrete or cement material in the formation of the body portion 1 of the tie. In this connection it will also be understood that the term "concrete body portion" is simply intended to include the concrete envelop or filling material for the tie proper which essentially consists of the metallic bars and the cushions associated therewith in the manner hereinafter more

fully explained. As above pointed out, the present invention is not restricted to any particular kind of concrete or cement material in the formation of the tie, and the term 5 "concrete" is employed in a broad sense to include not only what is known as regular concrete and cement composition, but also to include compositions made up of asphalt, broken stone, and sand, or equivalent combinations. The said concrete body portion 10 of the tie is intended to preserve the conventional outline and dimensions of the ordinary wooden cross ties, and is designed to be molded and compressed about the interior bars 2 by any suitable or approved means to 15 provide a tie of sufficient weight and having the necessary bearing surfaces necessary to properly hold it in the ballast, and to meet the traffic requirements.

20 A distinctive feature of the invention resides in the form and arrangement of the interior metallic bars 2 and their relation to the other parts of the tie structure. Referring to these bars, it will be observed that 25 the same are of the flanged type of metal bars and are preferably of that design commonly known as Z bars, which are provided with upper and lower oppositely disposed flanges 3 and 4, respectively. In the embodiment 30 of the invention shown in the drawings, a pair of the Z bars 2 is preferably employed, the same being arranged in opposite parallel relation, and co-extensive, as both 35 of said bars extend lengthwise of the concrete tie body and terminate close to the ends of said body, as plainly shown in Fig. 1 of the drawings.

In connection with the mounting of the oppositely arranged bars 2, it will be observed 40 that the upper horizontal flanges 3 thereof are turned outwardly from the vertical webs of the bars and are embedded in the top portion of the concrete body below the plane of the top surface of said body, 45 while the lower horizontal flanges 4 of the opposite bars are turned inwardly toward each other to provide supporting bases for the rail bearing cushions 5, to be presently referred to.

50 In regard to the mounting of the frame bars 2, it may be further explained that any suitable devices or expedients may be resorted to for firmly bonding the bars in the concrete body, and also for tying said bars 55 against lateral movement or displacement, but practical means for accomplishing these results are shown in the drawings. Referring thereto, it is to be noted that each of the bars 2 may be provided in the body portion 60 thereof with a plurality of bonding holes 6 arranged in any desired number or position, and designed to permit concrete or cement material to bond itself in said holes and thereby more firmly bond or bind all 65 the concrete into one mass and thus prevent the bars from splitting it up into separate pieces thus disintegrating the tie. The means shown for tying the opposite bars together to lock or secure the same against lateral movement or displacement and also to brace them against lateral strains, consists in the employment of upper and lower tie bars arranged transversely of the tie body and having suitable rigid connection with the opposite bars. In the arrangement 70 shown, there may be employed a series of upper tie bars 7 located at suitable intervals throughout the length of the tie and transversely disposed with reference thereto, so as to connect the opposite frame bars 2 at 75 their upper edges. The said upper tie bars or bracing ties 7 may be conveniently interlocked or connected with the frame bars by providing the said tie bars at their terminals with downturned engaging hooks 8 80 engaging over the outer edges of the upper flanges 3 of the frame bars. Also, in connection with said upper series of tie bars 7, there may be employed, as shown, a corresponding series of lower tie bars 9 likewise 85 disposed transversely of the tie body and arranged at suitable intervals. The said lower tie bars 9 are shown as extending transversely between the opposite frame bars 2 directly over the bottom flanges 4 thereof 90 and conveniently interlocked or connected with the frame bars by means of T fastening heads 10 provided at the ends of said bars 9 and having a detachable interlocking engagement with the T-shaped keeper holes 11 95 piercing the frame bars 2.

Referring to the mounting of the rail bearing cushions 5, these cushions are located at points in the tie body where bearing supports are to be provided for the opposite track rails, and at such points the tie body is provided with what may be termed retaining pockets 12 for the cushions. At the points where the pockets 12 are to be provided, the concrete or cement material 100 is omitted from the space between the vertical webs of the opposite bars 2 so that when the bearing cushions 5 are introduced into the pockets, said cushions will register snugly between the said webs of the opposite frame bars 2 and rest directly on the upper surfaces of the bottom supporting flanges 4, as plainly shown in Figs. 1, 2 and 3 of the drawings. The snug, registering, fit of the cushions 5 between the oppositely 110 located frame bars 2 effectually secures said cushions against movement laterally of the tie body. Movement or displacement of the cushions in a direction longitudinally of the tie body, and hence transversely of the railway track, is prevented by providing the frame bars with a plurality of laterally and inwardly deflected abutment projections 13 arranged in a manner to constitute metallic ends for the pockets 12. The abutment pro- 115

120

125

130

jections may be provided in various ways, but a simple and practical construction is shown in the drawings, and resides in making said abutment projections 13 in the form 5 of rectangular wings punched out directly from the metal bodies of the bars 2 so as to be disposed at approximately right angles thereto. Furthermore, the abutment projections 13 of each bar 2 are preferably 10 struck out from the bar in pairs, and the separate pairs are arranged in opposite relation on the bar at the points where both of the retaining pockets 12 are located so that, for each retaining pocket 12, each frame bar 15 2 has two pairs of abutment projections 13 respectively at opposite ends of the retaining pocket. Furthermore, it is preferable to arrange the abutment projections 13 of each pair in spaced relation, one above the other, 20 so that the concrete material fills in the space between said projections and about the edges thereof, thereby closing in the ends of the pockets 12 while permitting the cushions 5 to abut directly against the said abutment 25 projections.

The foregoing constitutes a thoroughly reinforced and substantial construction for retaining the oppositely located cushions 5 in proper position in the tie body, but in this 30 connection, an additional feature that may be utilized is that of inclining the abutment projections 13 slightly from a perpendicular plane so as to make the retaining pockets 12 of a downwardly tapering form so that by 35 correspondingly beveling or inclining the ends of the cushions 5, the latter are in effect wedges which tightly wedge themselves in their retaining pockets under the application of the load, thus securing a very 40 rigid mounting for the individual cushions.

The individual cushions 5 for the opposite track rails R consist of short lengths or blocks of wood which are capable of receiving the ordinary rail fastening spikes, rail-way, lag screws, or other track fastenings 45 adapted for use in connection with the ordinary wooden ties. It is also the purpose of the present invention to preferably employ cushions 5 made up of two or more sections 50 or blocks of wood arranged in closely matching relation and tightly fitted into the retaining pockets as suggested by the illustration in Fig. 3 of the drawings. And, it is preferable to so arrange the wooden cushions 55 5 as to dispose the grain vertically or end-wise of the vertical thrust of the load, thus providing a more effective and durable support for the rails. It is also to be noted that the bearing cushions 5 are of sufficient height 60 to project above the plane of the top surface of the tie body to hold the rails out of contact with the latter, and by resting the supporting wooden cushions near the bottom of the tie body on the bottom supporting 65 flanges 4, it will be apparent that a very

deep cushion is provided for the rails, and that the load is carried first to the bottom flanges of the frame bars and then transferred through the vertical webs thereof to the top flanges 3, thereby securing an effective and uniform distribution of the load throughout the tie body. 70

From the foregoing, it is thought that the general principles and essential features of the invention will be readily understood without further description, but it is also to be understood that various changes in the form, proportion, and minor details of construction may be resorted to without departing from the spirit or sacrificing any of the 75 advantages of the invention. 80

I claim:—

1. A tie comprising a concrete body, a vertically arranged bar embedded therein and provided at its lower edge with a supporting base, and rail bearing cushions seated 85 on said base.

2. A composite tie comprising a concrete body, vertically arranged interior frame bars provided at their bottom edges with supporting bases, and rail bearing cushions seated 90 on said bases.

3. A composite tie comprising a concrete body, vertically arranged interior frame bars provided at their bottom edges with in-turned supporting flanges, and bearing cushions seated on said flanges. 95

4. A composite tie comprising a concrete body, vertically arranged interior bars provided at their bottom edges with supporting 100 flanges, and bearing cushions seated on said flanges and projecting above the top surface of the tie.

5. A composite tie comprising a concrete body, incased vertically arranged Z bars, 105 and wooden cushions seated on the bottom flanges of said bars.

6. A composite tie comprising a concrete body, incased vertically arranged Z bars, 110 and wooden cushions seated on the bottom flanges of said bars and projecting above the top surface of the tie.

7. A composite tie comprising a concrete body, vertically arranged incased frame bars having bonding holes for the concrete material, bracing ties having an interlocked connection with the frame bars, and bearing 115 cushions for the rails.

8. A composite tie comprising a concrete body, incased Z bars having their top flanges 120 outturned and their bottom flanges inturned, and wooden cushions arranged between the bars and seated on the bottom flanges thereof.

9. A composite tie comprising metallic 125 frame bars having supporting bases, a concrete body incasing said bars and having retaining pockets provided with end abutments, and rail bearing cushions arranged in said pockets and seated on said bases. 130

10. A composite tie comprising a concrete body having cushion retaining pockets, incased metallic frame bars provided with laterally projecting abutments arranged at the 5 ends of the pockets, and rail bearing cushions seated within the pockets between said abutments.
11. A composite tie comprising a concrete body provided with cushion retaining 10 pockets, incased metallic frame bars provided with punched out abutment projections located at the ends of said pockets, and bearing cushions seated in said pockets.
12. A composite tie comprising a concrete 15 body having cushion retaining pockets, incased Z bars provided with punched out, inwardly deflected wings constituting abutment projections located at the ends of the pockets, and bearing cushions seated in said 20 pockets.
13. A composite tie comprising a concrete body, incased Z bars having bonding openings, and bearing cushions seated on the lower flanges of said bars.
- 25 14. A tie comprising vertically arranged
- Z bars, and wooden cushions seated on the bottom flanges of said bars and projecting above the surface of the ties.
15. A tie comprising Z bars having their top flanges outturned, and their bottom 30 flanges inturned, and wooden cushions arranged between the bars and seated on the bottom flanges thereof.
16. A tie having Z bars with retaining pockets of tapering form, and wedge shaped 35 bearing cushions seated in said pockets and having a support on the lower flanges of said Z-bars.
17. A tie comprising Z bars, and wooden bearing cushions located between them and 40 supported by the lower flanges of the Z bars, said cushions being arranged so as to prevent the grain endwise to the rail base.

In testimony whereof I hereunto affix my signature in the presence of two witnesses. 45

BENJAMIN WOLHAUPTER.
